Inventor
F.A. Goodnow

By Watson E. Coleman
Attorney

UNITED STATES PATENT OFFICE.

FRED A. GOODNOW, OF CHICAGO, ILLINOIS.

EXHIBITING DEVICE.

1,361,981.

Specification of Letters Patent.

Patented Dec. 14, 1920.

Application filed May 27, 1920. Serial No. 384,781.

To all whom it may concern:

Be it known that I, FRED A. GOODNOW, a citizen of the United States, residing at Chicago, in the county of Cook and State of Illinois, have invented certain new and useful Improvements in Exhibiting Devices, of which the following is a specification, reference being had to the accompanying drawings.

10 This invention relates to certain improvements in exhibiting devices and has relation more particularly to a device of this general character especially designed and adapted for use in connection with pictures and the like, and it is an object of the invention to provide a device of this general character with novel and improved means whereby the same may be supported in a desired position. It is also an object of the invention to provide a novel and improved device of this general character including an outer panel of glass or other transparent material and a back plate of metal or other opaque material, together with means for effectively 25 maintaining said plates in assembled relation, said means also being comprised in a medium whereby the assembled frame may be supported in desired position.

The invention consists in the details of 30 construction and in the combination and arrangement of the several parts of my improved exhibiting device whereby certain important advantages are attained and the device rendered simpler, less expensive and 35 otherwise more convenient and advantageous for use, as will be hereinafter more fully set forth.

The novel features of my invention will hereinafter be definitely claimed.

40 In order that my invention may be the better understood, I will now proceed to describe the same with reference to the accompanying drawings, wherein:

Figure 1 is a view in front elevation of an 45 exhibiting device constructed in accordance with an embodiment of my invention.

Fig. 2 is an enlarged vertical sectional view taken through the device as illustrated in Fig. 1.

50 Fig. 3 is an elevational view of the supporting member as disclosed in Fig. 2.

Fig. 4 is a view in rear elevation of the device as herein disclosed with the supporting member omitted.

55 Fig. 5 is a detail sectional view taken substantially on the line 5—5 of Fig. 4.

Fig. 6 is an inside elevational view of the outer holding plate comprised in the clamping means herein disclosed, and

Fig. 7 is a fragmentary view in perspective of one of the arms comprised in the clamping means as herein set forth.

As disclosed in the accompanying drawings, P denotes the front plate of my improved device herein disclosed in the form of a five-pointed star and the margins of the plate P are defined by the rearwardly directed flanges 1. The inner or meeting end portions of adjacent flanges 1 at their outer or free edges are provided with the webs or lugs 2 for a purpose to be herein-after more particularly referred to. The plate P, with its flanges 1 and webs 2 is formed of glass or other transparent material so that visual access may be had therethrough.

B denotes a back plate of metal or other opaque material and which is also herein disclosed in the form of a five-pointed star and which is adapted to snugly engage and overlie the rear face of the plate P, with the marginal portions thereof defined by the outstanding flanges 3 having close contact with the flanges 1 of the plate P.

The central portion of the plate B is provided with a slight depression 4 herein disclosed as circular and which provides a compartment or chamber 5 to receive a photograph, picture, or other article to be exhibited.

6 and 7 denote two disks in superimposed overlying relation, each provided at its axial center with an opening 8. Extending through the opening 8 is the headed shank or bolt 9 with which is engaged a clamping nut 10 whereby the disks 6 and 7 are maintained in requisite assembled relation and which shank or bolt 9 also serves for an additional purpose to be hereinafter more particularly referred to.

The outer disk 7 is provided with a plurality of radially disposed grooves or channels 11 in each of which is slidably disposed an end portion of an elongated arm 12. The portion of the arm 12 within the groove or channel 11 is provided longitudinally thereof with the slot 14 through which is disposed the clamping screw or bolt 15. The bolt 15, in the present embodiment of my invention, is loosely disposed through the outer disk 7 and in threaded engagement with the inner disk 6. By this means, the arm 12

may be longitudinally adjusted as required and particularly to facilitate the requisite engagement of said arm with a web or lug 2.

The outer end portion of each of the arms 12 is provided with an inwardly facing hook member 16 which is adapted to interlock with a web or lug 2. In the present embodiment of my invention, an arm 12 coacts with each of the webs or lugs 2, so that when 5 the same are operatively engaged therewith the plates P and B are effectively clamped in assembled relation and particularly in view of the fact that the outer end portions of the arms 12 are substantially in contact 10 with the free edges of the flanges 3 with the head of the shank or bolt 9 substantially in contact with the central portion of the plate B.

S denotes a supporting member comprising 20 two arcuate or curved legs 17 arranged in convergence with their meeting ends integrally connected. The opposite or free ends of the arms 17 are provided with the feet 18 adapted for contact with a supporting 25 surface and which feet are curved in such a manner to prevent the same from scratching or otherwise marring said surface.

Integrally formed with the meeting ends 30 of the legs 17 is an angularly disposed extension or arm 19 provided with a longitudinally directed slot 20 through which is adapted to be directed the free end portion of the shank or bolt 9 hereinbefore referred 35 to and outwardly of the clamping nut 10. Engaged with the shank or bolt 9 is a second clamping nut 21 whereby the extension or arm 19 is held in substantially a fixed position with respect to the bolt or shank 9 in 40 accordance with the requirements of practice. The slot 20 permits an adjustment of the supporting member S to effect the maintenance of the assembled plates P and B upon a desired angle and also allows an adjustment to permit said assembled plates to 45 be further supported by two adjacent points of the star or upon a single point as may be preferred.

The upper portion of the legs 17 are connected 50 by the transversely disposed member 22 whereby the supporting member S in its entirety is materially strengthened or reinforced as it is of utmost importance that such member S be substantially rigid.

The outer end portions of the arms 12 are 55 provided with the threaded openings 23 in which are adapted to be threaded or otherwise engaged the eye members 24 so that when desired a cord or the like may be engaged with said eye members to suspend or 60 hang the assembled plates P and B and under which conditions the supporting member S is not employed. In practice, only two eye members 24 need be employed and such 65 members are engaged with the arms 12 in

accordance with the position it is desired that the points of the device assume with respect to the center thereof. It will be understood, however, that if preferred the assembled device can be suspended from one 70 eye member 24 and preferably from the eye member 24 shown at the lower part of the device as illustrated in Fig. 4.

Although not shown in the accompanying drawings, it is to be understood that the face 75 of the plate B exposed through the plate P may have arranged thereon any kind of ornamentation which will enhance the esthetic value of the device and while primarily it is my intention to place such ornamentation on the points of the plate B, it is to be understood that the central portion of said plate may also be ornamented as desired and in which instance it will not be necessary to apply a photograph, picture, or other 80 article, as it will be readily understood that if desired a mirror or any other article may be arranged at the central portion of the plate P or more particularly within the chamber 5 afforded by the depression 4. 90

I also do not wish to be understood as limiting myself to placing ornamentation upon the plate B because under certain conditions it may be of advantage to arrange such ornamentation on the inner face of the 95 transparent plate P.

From the foregoing description it is thought to be obvious that an exhibiting device constructed in accordance with my invention is particularly well adapted for use 100 by reason of the convenience and facility with which it may be assembled and operated, and it will also be obvious that my invention is susceptible of some change and modification without departing from the 105 principles and spirit thereof and for this reason I do not wish to be understood as limiting myself to the precise arrangement and formation of the several parts herein shown in carrying out my invention in practice except as hereinafter claimed. 110

I claim:

1. An exhibiting device of the character described comprising two plates, one disposed within the other, the first mentioned 115 plate having a depression for the reception of matter to be exhibited, each plate having rearwardly directed flanges disposed in engagement with each other, and fastening means engaged with one of said plates and 120 extending over the flanges of said plates into engagement with the remaining plate, whereby the engagement of the edges of the plates with each other is only visible from the rear portion of the device. 125

2. An exhibiting device of the character described comprising a transparent plate and an opaque plate, the opaque plate being disposed within the transparent plate and having a depression for the reception of 130

matter to be exhibited, means for securing and supporting said plates comprising a plate having a plurality of radiating channels, arms adjustably mounted in said channels and engaged with the edges of the plates.

3. An exhibiting device of the character described comprising a transparent and an opaque plate, the opaque plate being disposed within the transparent plate and having a depression for the reception of matter to be exhibited, and means for securing and supporting said plates comprising a plate having a plurality of radiating channels, arms having one of their end portions disposed within the channels, the opposite ends of the arms extending over the edges of the plates into engagement with the side portions of the transparent plate.
- 10 4. An exhibiting device of the character described comprising a transparent and an

opaque plate, the opaque plate being disposed within the transparent plate and having a depression for the reception of matter to be exhibited, means for securing and supporting said plates comprising a plate having a plurality of radiating channels, arms having one of their end portions disposed within the channels, the opposite ends of the arms extending over the edges of the plates 25 into engagement with the side portions of the transparent plate, a bolt extending through the central portion of the plate supporting the arms, a stand slidably mounted on said bolt, and means carried by the bolt 30 to normally prevent movement of the stand, said bolt being also arranged to limit movement of the arms toward each other.

In testimony whereof I hereunto affix my signature.

FRED A. GOODNOW.
